AUTOMATIC SALIVA KEY FOR TROMBONES

William H. Maxwell, Elberton, Ga.

Application February 16, 1946, Serial No. 648,137

8 Claims. (Cl. 84—397)

1

The present invention relates to certain structural refinements and improvements susceptible of being incorporated in a conventional slide trombone and has reference in particular to an improved moisture release valve or key.

It is a matter of common knowledge that the outer U-slide of a trombone is provided on its bend with a so-called water key. This is a simple valve with a cork operating against a relief seat, said valve being on an arm and said arm being pivotally mounted on the bend and provided with a suitable finger key. This water key, in actual practice is opened by hand whenever the user deems it advisable to drain the slide. Due to its position and construction it is difficult of access although it is susceptible of skillful operation by long experienced performers, it is possessed of considerable nuisance value to beginners and others who find it difficult to handle while playing.

The present invention has to do with a saliva or moisture relief valve of a similar construction located also on the bend of the U-slide, means being provided for automatically tripping and opening of the valve at a predetermined stage, and additional means being provided to cushion the mechanical action of parts and elements to render the overall result effective and conveniently reliable.

In carrying out the principles of the invention I have found it expedient and practicable to provide a curvature trip finger or cam, this being mounted on the terminal of one of the limbs of the inner relatively stationary slide, said finger coacting with a release pin and said pin being carried by the cork equipped valve cup in order to accomplish the desired results in timed relationship.

Another object of the invention is to provide special spring containing cuffs these to telescopically receive the inner adjacent ends of the parallel limbs of the U-slide, these springs constituting cushioning elements and also serving to let the performer know approximately when the U-slide has been pulled in to a point sufficient to trip the moisture release valve.

Other objects, features and advantages of the invention will become more readily apparent from the following description on the accompanying illustrative drawings.

In the drawings, wherein like numerals are employed to designate like parts throughout the views:

Figure 1 is an elevational view of a trombone in which the U-slide is constructed with a so-called

2

automatic saliva or moisture release valve constructed in accordance with the specific principles of the instant invention.

Figure 2 is an enlarged fragmentary view, partly in section and partly in elevation, of the inner end portions of the inner and outer sections which go to make up the complete slide.

Figure 3 is an enlarged fragmentary view showing, in section, the bend of the U-slide and detailing the construction of the valve and trip means.

Referring now to the drawings by distinguishing reference characters it will be seen that the horn, generally speaking, is made up of the bell equipped section or unit A and the so-called 15 swingable and shiftable slide unit B. The latter is detachable as a unit from the part A and in itself composed of a so-called inner slide 5 and a companion relatively shiftable outer slide or so-called U-slide 6. The shank 7 on the inner 20 slide is detachably connected with a socket fitting on the section A as indicated in Figure 1 and a socket 8 serves to accommodate the shank of the cup mouth-piece 9. The spaced parallel tubular limbs 10 and 11 are joined as at 12. These 25 parts are all conventional. It is to be noted in Figure 2 that cuff-like sleeves or adapters 13 are provided as a part of the present invention and these surround the inner end portions of the arms or limbs 10 and 11 and rest against the elbow fittings 14. These sleeves serve to accommodate coiled cushioning and buffer springs 15 which serve in a manner to be hereinafter more specifically set forth.

The relatively shiftable U-slide 6 includes 35 tubular limbs or arms 16 joined at their outer or right hand ends by the customary U-bend 17. This part 17 is provided with the usual outstanding drain hole 18 for drainage of saliva, and moisture. This part 18 constitutes the usual 40 drain hole and valve seat combined. The valve comprises a cup 19 with a cork pad 20 located therein and engaging the valve seat. The cup is carried on an arm 21 and the arm is hingedly mounted as at 22 on the bend. A closing spring 45 23 is provided and this is a leaf-type spring and one end is fastened by set-screw 24 on the mount 25. The other end of the spring is attached to the cup. Also as brought out in Figure 3, the cup is provided with an integral pin or stem which 50 constitutes an actuating element and this is indicated at 26. It is formed integral with the central part of the cup and extends into and interiorly beyond the valve seat 18. The inner end thereof coacts with the curvate trip or cam 27 on 55 the limb 11. The pin serves not only as an

actuating element but also as a mount for the cork 20. That is to say, the cork can be fitted on the threaded portion 28 thus obviating the necessity of gluing the cork in the cup as is ordinarily done. Thus, the pin has a double acting feature in that it serves as a retainer for the cork and also as the actuating member for opening and closing the valve. This opening and closing movement is accomplished by the cam coaction of the trip or trigger finger 27 with the inner end of said pin.

Referring again to the buffer springs 15, these not only function as cushioning elements, but primarily as warning means. That is to say, as the arms 16 telescope into these sleeves 13 and rest against the springs, the springs are put under compression. When a certain stage of compression is reached, this indicates that the trigger or trip finger 27 has now reached the pin 26 and is about to press against same and to force the moisture valve open. Hence, the spring means is both a signal and warning as well as a cushioning feature.

The normal operation of the U-slide on the inner slide section during regulation play does not operate the moisture valve means. When, however, the slide 6 is completely "in" and the arms 16 compress the springs 15, the coils continue to compress until a predetermined stage is reached, whereupon the trigger finger 27 now reaches the pin 26, exerts a cam influence or stress against said pin and springs the valve open against the tension of its closing spring 23.

The incorporation of the present invention, which lends itself adaptable for embodiment in a regular trombone, obviously and proportionately increases the over-all efficiency of the instrument. However, the invention is quite simple and hence, its adoption and use does not add materially to the cost of manufacture or complicate other commercial requirements.

It is clear that the present disclosure, the drawings and description, is for the purpose of illustration only and that this invention includes all modifications and equivalents which fall within the scope of the adjoined claims.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

I claim:

1. In a trombone, a standard type slide embodying inner and outer telescoping slides, the outer slide being a customary U-slide, said U-slide being provided in its bend with a moisture drain hole, an exteriorly arranged spring closed valve coacting with and normally closing said hole, and coacting means between the inner slide drain hole and valve for opening the valve, under predetermined circumstances and at a predetermined stage of relative movement of said slides, whereby to automatically drain moisture by way of said drain hole.

2. In a trombone of the class described, a slide embodying an inner slide including spaced paral-

lel tubular limbs, an outer U-slide having corresponding tubular limbs telescopically receiving and slidable upon said first named limbs, the bend of said U-slide being provided with a moisture drain hole, a spring pressed valve coacting with and normally closing said hole, an actuating element mounted on said valve extending interiorly into the bend by way of said drain hole, and a coacting element on the adjacent end of one of the limbs of said inner slide engaged for operation with said first-named element.

3. In a trombone of the class described, a slide embodying an inner slide including spaced parallel tubular limbs, an outer U-slide having corresponding tubular limbs telescopically receiving and slidable upon said first named limbs, the bend of said U-slide being provided with a moisture drain hole, a spring pressed valve coacting with and normally closing said hole, an actuating element carried by said valve extending interiorly into the bend by way of said drain hole, and a reciprocatory element on the adjacent end of one of the limbs of said inner slide coacting with said actuating element, said last named element being in the form of a longitudinally bowed trigger finger.

4. In a trombone construction of the class described an inner slide unit including spaced parallel tubular limbs, the outer end of one of said limbs being provided with a projecting longitudinally bowed finger, said finger constituting a trip and being adapted, when in use, to slidably contact and impart motion to an actuating element on a saliva drainage valve.

5. As a component part of a slide construction for trombones, a U-slide including the customary spaced parallel tubular limbs and adjoining U-bend, said bend being provided with a drain hole and an outstanding seat forming neck, an arm pivoted on said bend, a cup carried by said arm, a pad in said cup engaging said seat, and a pin carried by said cup and extending into the interior of the bend by way of said drain hole and neck.

6. As a component part of a slide construction for trombones, a U-slide including the customary spaced parallel tubular limbs and an adjoining U-bend, said bend being provided with a drain hole and an outstanding seat forming neck, an arm pivoted on said bend, a cup carried by said arm, a pad in said cup engaging said seat, and a pin carried by said cup and extending into the interior of the bend by way of said drain hole and neck, and an elongated leaf spring anchored at one end on the exterior of said bend and having its opposite end connected with said cup in a manner to press the pad against said neck.

7. In a trombone slide construction of the class described a U-slide including a bend having a saliva drain hole, an arm pivoted exteriorly on said bend, a valve cup carried by said arm, said cup being provided with a laterally projecting pin centrally mounted in said cup, said pin extending concentrically into the interior of the bend by way of said drain hole, said pin being screw-threaded, and a centrally apertured cork fitting into said cup and mounted and fastened on the threaded portion of said pin, in the manner and for the purpose described.

8. In a trombone of the class described, an inner slide including spaced parallel limbs surrounded at their inner ends by sleeves, coiled springs surrounding said limbs and confined in

said sleeves, a U-slide having tubular limbs slideable on said first named limbs, the inner ends of said U-slide limbs telescoping into said sleeves, a drain valve on the U-bend, and a trip finger on one of the first named limbs, together with an operating connection between the trip finger and valve.
